CLAIM

The ornamental design for a combined medallion and
chain, as shown and described.

DESCRIPTION

FIG. 1 is a front elevational view of a combined medallion
and chain showing my new design;

FIG. 2 is a rear elevational view thereof;

FIG. 3 is a left side elevational view taken from FIG. 1
of the medallion with the chain removed;

FIG. 4 is a right side elevational view taken from FIG.
1 of the medallion with the chain removed.
